UNITED STATES PATENT OFFICE.

WILLIS MCKEE, OF ELYRIA, OHIO, ASSIGNOR TO THE ELYRIA IRON & STEEL COMPANY,
OF ELYRIA, OHIO, A CORPORATION OF OHIO.

APPARATUS FOR REMOVING BURS.

1,135,705.

Specification of Letters Patent. Patented Apr. 13, 1915.

Application filed December 6, 1913. Serial No. 804,985.

To all whom it may concern:

Be it known that I, WILLIS MCKEE, a citizen of the United States, residing at Elyria, in the county of Lorain and State of Ohio, have invented a certain new and useful Improvement in Apparatus for Removing Burs, of which the following is a full, clear, and exact description, reference being had to the accompanying drawings.

10 In the manufacture of metal tubes it is customary to make them in long lengths and sever them by a high speed saw. Such operation leaves a number of burs on the outside and inside edges of the severed ends. 15 These burs are hardened by the heat of the sawing operation and the air cooling, so that it is very difficult to remove them by cutting. The difficulty of removal is particularly great in the case of the burs on the inside edge, and the present invention is for a 20 mechanism which will quickly and satisfactorily remove such inside burs.

An object of this invention is to provide 25 such an apparatus which shall be simple in construction, efficient and rapid in operation and which shall leave a comparatively smooth surface on the inside of the severed end.

Another object is to so construct such a 30 device that several of them may be mounted on a common support and driven from a single shaft.

Still another object is to so arrange these 35 devices as to provide for various lengths of tubes being readily held while being operated upon, while allowing quick removal from the machine.

The invention is hereinafter more fully 40 described in connection with the drawings, other objects will become apparent in the specification and the essential characteristics are set forth in the claims.

Figure 1 is a front elevation of two of the devices for removing burs, mounted on 45 suitable common support and driven from a common shaft; Fig. 2 is a sectional side elevation of the same; Fig. 3 is a detail of the tool for removing the bur and a device for holding the end of the tube; Fig. 4 is a 50 sectional detail of the same taken on a plane at right angles to the plane of Fig. 3; Fig. 5 is a horizontal sectional detail showing the tool and a tube, taken on the line 5—5 of Fig. 4.

10 indicates the main shaft which is 55 mounted in suitable bearings at 11 and 12, carried by upright support members 14, which are bent forwardly at their lower ends forming feet 15, by which they may be secured to the floor. At their upper ends these 60 supports are bent forwardly and then upwardly at 16 and secured to a transverse channel member 17, which has its flat side facing the front and its flanges extending rearwardly. Just beneath this channel member 65 17 is a transverse member 19 parallel therewith and secured at each end to the supports 14. The foregoing comprises the frame support for my bur removing mechanism.

Rigidly mounted on the shaft 10, are eccentric disk portions 20 revoluble in eccentric straps 21, the upper part of each of which is made rigid with an eccentric arm 22 pivotally secured at its upper end to a rock 70 lever 24. The rock lever 24 is intermediately pivoted between ears 25, made rigid with a head 26 which has laterally extending flanges 28 by which the head is secured with bolts to the channel member 17, and which has a 75 rearwardly extending flange 29 overhanging and engaging the upper edge of this channel member. The head 26 projects forwardly from the flange 28 and is provided in its front face with a rectangular trough 30. 80 This trough is open at its lower end and front side, and is closed by a web 32 at its upper end. Fitted into this trough is a guide block 34 having a rectangular exterior and held in place at the upper end of 85 the trough by set screws 35. The interior of the block is cylindrically bored to fit loosely over the end of a tube, and the upper portion of the block extends entirely around the tube 36 as shown at 37. Below this portion 90 37, the block is cut away on the front side as indicated by broken lines at 38, to allow the end of the tube being readily inserted. When the end of the tube is in the block its upward movement is limited by an 95 end member 40 rigid with the block and provided with a notch partially surrounding a plunger 42.

The plunger 42 is carried by a head 43 pivoted to the forward end of the rock lever 100 24. It extends downwardly, having its lower end normally within the block 34, and is provided at its lower end with a trans-

verse slot 44 into which is fitted a tongue 45 formed on a cutting tool 46. This tool has a partially cylindrical exterior and has at its upper end an arcual-shaped active edge 48. The interior surface is made partially cylindrical and is adapted to substantially fit the outer surface of the plunger 42. A pin 49 passing through the lower end of the plunger and tongue 45, pivotally secures the tool to the plunger. This tongue is provided with a lug 50 adapted to engage the upper end of the slot to limit the outward movement of the plunger to prevent it engaging the portion 37 of the guide block. Although I have shown a projection on the tongue 45 to limit the outward movement of the tool, I do not wish to be limited to this construction, as any suitable means might be used although as shown, the tool tends to fall outwardly by gravity, any suitable means may be used to press the tool outwardly.

The lower end of the tube 36 may be held while the bur is being removed, by a block 52 which is provided with a slot 53 on its upper side. This slot has flaring sides adapted to engage various diameters of tubes, and a bottom which slants downwardly toward the front to provide additional adjustment for varying lengths of tubes. This block is carried on a table 54 having an upwardly extending leg 56 adapted to be secured by bolts 57 to an upright support 58 having a foot 59 at its lower end by which it is secured to the floor and having its upper end secured by a suitable bolt to the transverse bar 19. This support is provided with a series of holes 60 evenly spaced apart, through which the bolts 57 are adapted to pass allowing the vertical adjustment of the table 54. Thus it will be seen that the block 52 may be raised or lowered to obtain approximate adjustment for various lengths of tubes, and may be slid backward and forward on the table 54 until the bottom of the slot 53 engages the lower end of the tube, the sides of the slot providing a rest by which the tube may be held steady while the bur is being removed. When the block is once set in position, any number of tubes of the same size may be operated upon without moving it.

The burs frequently project far enough across the interior of the tube so that the space for the entrance of the tool and its holder is choked, and considerable force must be exerted to effect such entrance. The incline of the support provides for this, as it enables a comparatively small force exerted horizontally on the lower end of the tube to jam the upper end upwardly across the tool.

In operation, power is supplied to a suitable pulley 64 on the shaft 10, to rotate the shaft and the eccentrics, oscillating the

levers 24 and causing the plungers 42 to reciprocate vertically. A tube 36 having an inwardly projecting bur 65 at its upper end, (any bur on the outside of the end having been previously removed) is inserted into the guide block 34 and its lower end is guided by the groove in the block 52. The tool being pivoted on the plunger readily moves inwardly, allowing the plunger and tool to enter the end of the tube on the down stroke, and on the up stroke the tool presses outwardly against the inner surface of the tube. The arcual edge rides freely over the comparatively smooth parts of the inner surface of the end of the tube, but engages and breaks off a portion of the bur 65, the upward movement of the tube being prevented by the end member 40 of the guide block, which in turn engages the web 32 of the head 26. The operator holding the tube during this operation, rotates it slightly by hand for a portion of a rotation, bringing a fresh part of the bur into the path of the tool, to be trimmed off on the next up stroke of the plunger. This trims off the entire bur 65 leaving a smooth inner surface at the end of the tube.

As will be seen from Fig. 1, I may readily arrange several of these mechanisms to be operated by one shaft 10 and mount them on the same transverse members 17 and 19, it being only necessary to extend these members and the shaft, as indicated at the left of this figure. By this arrangement, I provide a mechanism on which several operators may work at one time, with the greatest economy of power and floor space, as well as providing simple and cheap construction of the mechanism.

Having thus described my invention, what I claim is:

1. In an apparatus of the character described, the combination of a reciprocable plunger adapted to enter a pipe-like tube, a tool carried by the plunger and adapted to bear against the inner surface of the tube, an abutment against which an end of the tube may bear when the plunger and tool are within the tube, and an abutment against which the opposite end of the tube may simultaneously bear.

2. In an apparatus of the character described, the combination of a tool, a reciprocating member pivotally carrying the tool, and a guide for the end of a pipe-like tube adjacent the tool, means for moving said tool into and out of the end of the tube, said tool being adapted to press outwardly against the inner surface of the tube, whereby an inwardly turned bur at the end of the inside surface may be broken off by the tool.

3. The combination of a means for holding a pipe-like tube in a removable manner, a plunger, means for reciprocating the plunger within the end of the tube, a tool pivoted

to the plunger and extending alongside of it whereby it may engage inwardly turned burs at the end of the tube, and means for limiting the movement of the tool away from the plunger.

5. The combination of a guide for the end of a round pipe-like tube, a plunger adapted to enter the end of the tube, and a tool having a partially cylindrical outside surface of substantially the same radius as the inner surface of the tube, the inside surface of the tool being adapted to substantially fit around the plunger, said tool being pivoted to the end of the plunger and adapted to swing outwardly, and means for reciprocating the plunger.

6. The combination of a reciprocating tool adapted to enter the end portion of a pipe-like tube and engage an inwardly turned bur at the end thereof, a guide adjacent the tool for loosely embracing the outside of the tube near that end, allowing the tube to be turned while in the guide, and an abutment adapted to extend over and engage that end of the tube.

7. The combination of a guide loosely fitting the exterior of one end of a round pipe-like tube, a stop adapted to abut the end of the tube to prevent end movement thereof, a plunger adapted to enter the end of the tube, a tool having an arcual edge pivoted to the plunger, means for reciprocating the plunger and tool, and means for steadyng the other end of the tube.

8. The combination of a guide loosely fitting the exterior of the end of a round pipe-like tube, a plunger adapted to enter the end of the tube, a tool pivoted to the plunger and having an arcual edge, means for reciprocating the plunger and tool, and a stop adapted to abut the end of the tube to prevent end movement thereof.

9. The combination of a reciprocating tool, a guide adjacent to the tool and adapted to position one end of a pipe-like tube to be trimmed, and an adjustable block having a slanting surface upon which the other end of the tube may rest.

10. The combination of a guide for one end of a pipe-like tube, a stop abutting the end of the tube adjacent said guide, a reciprocating cutter adapted to remove by breaking off an inwardly turned bur in the end of the tube, a block having a slanting surface adapted to engage the other end of the tube, and an adjustable support on which said block is mounted.

11. The combination of a cylindrical guide for one end of a pipe-like tube, a stop abutting the end of the tube adjacent said guide, a reciprocating tool adapted to remove an inwardly turned bur in the end of the tube, means for steadyng the lower end of the tube comprising a block having a slanting surface adapted to engage the other end of the tube and a tapered groove adapted to engage the sides of the same, a support on which said block is mounted, and means for adjusting the support longitudinally of the tube.

12. The combination, with means for holding a round pipe-like tube, of a tool having an arcual edge adapted to enter the end of the tube, a lever pivotally carrying the tool, a shaft, and connections between said shaft and said lever for oscillating the lever to reciprocate the tool.

13. In an apparatus of the character described, the combination of a tool, means for reciprocating the tool, means for holding a tube extending over the tool in position to enable the tool to trim off inwardly turned burs on the end of the tube, and means having a cam surface for engaging the end of the tube for forcing the tube longitudinally over the tool.

14. In an apparatus of the character described, the combination of a tool, means for reciprocating the tool, means for holding a pipe-like tube at the upper end extending over the tool in position to enable the tool to trim off by breaking inwardly-turned burs on the end of the tube, and a support for the lower end of the tube having a wedge-shaped groove with a slanting bottom whereby the tube may be forced longitudinally over the tool as the lower end is pressed inwardly to a position substantially in longitudinal alinement with the tool.

15. The combination of a reciprocating plunger, a tool carried thereby and projecting on one side of the plunger, an abutment on the opposite side of the plunger from the tool and adapted to extend over and engage the edge of a pipe-like tube surrounding the plunger and tool, said abutment leaving a free space beyond the end of the tube on the tool side of the plunger, and positioning means engaging the outside of the wall of the tube adjacent to that end.

16. The combination of a reciprocating plunger, a tool carried thereby and projecting at one side, an abutment adapted to extend across the end of a tube surrounding the plunger and tool, said abutment being extended to form a guide for the plunger on the opposite side from the tool.

17. The combination of a plunger, mechanism connected thereto for reciprocating the plunger, a tool pivoted to the plunger and adapted to lie alongside thereof extending from its pivot in a general direction toward

the driven end of the plunger, and a guide adapted to engage the wall of a pipe-like tube surrounding the plunger and tool.

18. The combination of a reciprocating plunger having a free end, a tool pivoted to the plunger adjacent to the free end and extending alongside of it away from such free end, a stationary guide extending around the plunger and tool and adapted to loosely embrace a tube surrounding the plunger and

tool, an abutment adapted to extend over that end of such tube, and an abutment adapted to engage the other end of the tube.

In testimony whereof, I hereunto affix my signature in the presence of two witnesses.

15

WILLIS MCKEE.
